ELECTRONIC CABINET

James G. Wells, Chicago, and Herbert C. Golz, Aurora,
Ill., assignors to Elgin Metalformers Corporation, Elgin,
Ill., a corporation of Illinois

Application May 14, 1956, Serial No. 41,466

Term of patent 14 years

(Cl. D26—5)

Fig. 1 is a perspective view of an electronic cabinet embodying our new design;

Fig. 2 is a top plan view thereof; and

Fig. 3 is a fragmentary side elevational view thereof, a portion being broken away for convenience in illustration.

The side not shown is like the side shown in Fig. 3. The rear side is plain.

The dominant features of our design reside in the portions shown in full lines.

We claim:

The ornamental design for an electronic cabinet, substantially as shown and described.
